UNITED STATES PATENT OFFICE.

FREDERICK DOBSON, OF BOSCOBEL, WISCONSIN.

PUMP ATTACHMENT.

SPECIFICATION forming part of Letters Patent No. 739,298, dated September 22, 1903.

Application filed September 5, 1902. Serial No. 122,216. (No model.)

To all whom it may concern:

Be it known that I, FREDERICK DOBSON, a citizen of the United States, residing at Boscobel, in the county of Crawford and State of Wisconsin, have invented a new and useful Pump Attachment, of which the following is a specification.

This invention relates to pump attachments.

10 The object of the invention is in a ready, simple, thoroughly feasible, and practical manner to equalize the power necessary to operate a pump, so that substantially as much power will be required to depress the pump-rod as to lift it and the column of water.

15 A further object is to obviate the employment of intricate parts in the construction of the device, thus, in the case of damage or breakage, to enable a mechanic of ordinary 20 ability to make the necessary repairs.

With these and other objects in view, as will appear as the nature of the invention is better understood, the same consists in the 25 novel construction and combination of parts 25 of a pump attachment, as will be hereinafter fully described and claimed.

In the accompanying drawings, forming a part of this specification, and in which like numerals of reference indicate corresponding 30 parts, there is illustrated one form of embodiment of the invention capable of carrying the same into practical operation, it being understood that the elements therein exhibited may be varied or changed as to shape, 35 proportion, and exact manner of assemblage without departing from the spirit thereof.

In the drawings, Figure 1 is a view in vertical section through an attachment constructed in accordance with the present invention. Fig. 2 is a view in perspective showing the manner in which the equalizing-spring is associated with its support. Fig. 3 is a perspective detail view of a nut for placing the equalizing-spring under the desired tension.

40 The device of this invention is equally adaptable for use in connection with an ordinary pump or with a windmill and in either case is to be disposed within the well, below the freezing-point thereof. For convenience 45 of illustration it is herein shown as adapted for use in connection with a windmill.

Referring to the drawings, 1 designates a

section of tubing constituting a spring-casing, which is threaded externally at each end for the reception of nuts 2 and 3, respectively, 55 the said nuts being adapted to have connected with them pipes 4 and 5, the former of which extends to the top of the well and the latter is connected with the cylinder, and as the manner of association of the pipes with 60 the parts named may be of any preferred character and as it will be well understood detailed illustration is deemed unnecessary.

Disposed on the interior of the upper portion of the spring-casing is a peripheral shoulder 6, upon which bears a power-equalizing spring-support 7, the same being a disk provided with a central orifice 8, a lateral orifice 9, and a radial slot 10. The orifice 8 is adapted to receive a connecting-rod 11, the upper end 70 of which is provided with a coupling 12 for connection with a pump-rod 13 and the lower end with a coupling 14 for engagement with a suction-rod 15.

Housed within the casing is a coiled power-equalizing spring 16, the upper terminal of which is formed into a whirl 17, disposed in a plane transverse to the length or axis of the spring and provided with a bend or offset 18 to engage the slot 10 and with a toe 80 19 to engage the orifice 9, the major portion of the whirl bearing flatly upon the support 7, as clearly shown in Fig. 2. The lower terminal of the spring is formed into a bend or offset 20, adapted to engage an open-ended 85 slot 21 in a nut 22, threaded upon the connecting-rod, the under side of the said nut being provided with a teat 23, to be engaged by a whirl 24, constituting the lower terminal of the equalizing-spring, and with an orifice 90 25, to be engaged by an upturned toe 26 of the said whirl. The spring is substantially of about one-half the length of the casing, and the nut 22 is equal in diameter to the same, and it will be seen that by turning the 95 nut upon the rod 11 the spring may be placed under requisite tension to cause equal balancing of power. As herein shown, the rod 11 is threaded for about one-half its length, thus to insure a range of movement of the 100 nut 22 to place the spring under the requisite adjustment for any contingency that might arise; but it is to be understood that the invention is not to be limited to this arrange-

ment, as it may be increased or diminished and still be within the scope of the invention.

By the arrangement of parts exhibited it will be seen that upon the downstroke of the pump-rod resistance will be presented by the spring which will be equal or substantially equal to that presented to the suction-rod on its lift, so that all jerking and unequal motion of the pump and suction-rods, with attendant danger of bending or breaking, will be positively obviated. Furthermore, provision is made by which the spring may be regulated to wells of different depth, thereby extending the range of usefulness of the device.

15 While the arrangement of parts herein shown has been found thoroughly effective in operation and will be found in a positive and reliable manner to perform the functions designed, it is to be understood that the invention is not to be limited to the exact details disclosed, as it will be obvious that various minor changes as to proportions of the various parts may be resorted to and still be within the scope of the invention.

25 Having thus fully described my invention, what I claim as new, and desire to secure by Letters Patent, is—

1. An equalizing device for pump-rods, comprising a coiled spring provided at each end 30 with a transverse whirl and adjacent thereto with an offset and a terminal toe, and relatively fixed and movable members for respective engagement by the terminal whirls of the spring, and each having a slot and an opening 35 to receive said offset and toe.

2. An equalizing device for pump-rods, comprising a rod, a coiled spring provided at each end with a transverse whirl and adjacent thereto with an offset and a terminal toe, and 40 relatively fixed and movable members for respective engagement by the terminal whirls of the spring, and each having a slot and an opening to receive said offset and toe, and said members also having openings respectively 45 to guide and engage said rod.

3. In a device of the class described, a casting provided in its upper portion with an inward-extending shoulder, a support resting upon the shoulder and provided with a central 50 orifice having a slot extending therefrom and with a lateral orifice, a connecting-rod having

its lower portion threaded, a tension-nut engaging the threaded portion of the rod and provided with an open-sided slot, and an equalizing-spring having its upper whirl provided with a bend to engage the radial slot and with a toe to engage the lateral orifice, and its lower whirl provided with a bend to engage the said open-sided slot. 55

4. In a device of the class described, a casting provided near its upper portion with an inward-extending shoulder, a support resting upon the shoulder and provided with a central orifice having a radial slot extending therefrom and with a lateral orifice, a connecting-rod having its lower portion threaded, a tension-nut engaging the threaded portion of the rod and provided with an open-sided slot and a downward-extending teat, and an equalizing-spring having its upper whirl provided with a bend to engage the radial slot, with a loop to bear upon the support and with a toe to engage the lateral orifice, and its lower whirl provided with a bend to engage the said open-sided slot and a loop to engage 75 the said teat. 70

5. In a device of the class described, a casting provided in its upper portion with a shoulder, a support resting thereon and provided with a central orifice having a radial slot extending therefrom and with a lateral orifice, a connecting-rod having its lower portion threaded, a tension-nut engaging the threaded portion of the rod and provided with an open-sided slot, a downward-extending 80 teat and a lateral orifice, and an equalizing-spring having its upper whirl provided with a bend to engage with the radial slot, with a loop to bear upon the support and with a toe to engage the lateral orifice, and its lower whirl provided with a bend to engage the open-sided slot of the tension-nut, a loop to engage the teat thereof, and a toe to engage the orifice. 85 90

In testimony that I claim the foregoing as my own I have hereto affixed my signature in the presence of two witnesses.

FREDERICK DOBSON.
